ROTARY MACHINE

Otto Sorge, Berlin, Germany

Application June 12, 1939, Serial No. 278,716
In Germany May 4, 1938

4 Claims. (Cl. 103—136)

This invention relates to an improved rotary machine to be used chiefly as vacuum pump, as well as compressor. I am aware of the existence of pumps of the type, in which radially movable blades are arranged in radial slots of a rotor arranged eccentrically in a stationary casing. The advantages obtainable by such machines are the greater the greater the number of revolutions of the same is, in that the specific output of the machine is correspondingly increased, but there increases also the centrifugal force to which the blades are subjected, this increase being far from being desired, in that it increases in the square of the number of revolutions. The frictional resistance between the blades and the inner circumferential wall of the casing is likewise increased, as is also, as a consequence thereof, the heating and, finally, also the consumption of power. It is, anyhow, possible, to overcome the undesired consequences mentioned by the provision of balance weights arranged counter to the blades, i. e. on the other side of the axis of the machine, and to connect the blades and said weights with one another, the purpose of these latter being to counterbalance the centrifugal force.

The various constructional forms of rotary machines of the above-mentioned type which have become known up to now suffer all especially from the two serious drawbacks that they are very expensive and operate uneconomically. It is, with said machines, indispensably requisite that the blades must be guided in the slots very accurately, which is true also of the guiding of the balance weights in said slots, and that accurate guiding requires excellent workmanship which renders the manufacture correspondingly expensive and necessitates, of course, also correspondingly much time, apart from the fact that the result is never completely satisfying, also as regards the output and the efficiency.

The above-mentioned drawbacks have now all been overcome by the present improved design which renders it, in fact, possible to attain double the efficiency by simplified means which do not require such very great care as regards the guidance of the blades and of the balance weight. This improved machine is illustrated diagrammatically and by way of example on the accompanying drawing on which Figure 1 is a transverse vertical section through the constructional form shown. Figure 2 is an axial section of that machine, the casing being omitted, and the figure being drawn to a slightly enlarged scale relatively to Fig. 1, and Figure 3 is a view

similar to Fig. 2 and shows a slightly modified constructional form of the machine.

On the drawing, *d* denotes the stationary casing which is provided with the branches *d*1 and *d*2 for sucking in the medium to be dealt with and for discharging it. Within said casing is eccentrically arranged the rotor which consists in this example of the halves *e*1 and *e*2 which are connected with one another by frontal disks *f* to which are affixed trunnion *g*, by the intermediary of which the rotor is rotated. The rotor halves *e*1 *e*2 are not accurate halves in that there is left between them a diametrically extending slot in which are located the blades *aa*1 and the balance weights *bb*1. These weights are arranged inside of the blades, and they are provided with radial bores through which extend rods *c* and *c*1 by which the weights and the blades are connected with one another in such a manner that each blade is connected with that weight which lies adjacent to the oppositely located blade, as appears particularly distinctly from Fig. 1. The rods pertaining to any one of the blades alternate with the rods pertaining to the other blade, as appears likewise particularly distinctly from Fig. 2. The rods serve as guide members for the weights, and this being so it is no more necessary to provide recesses in the blades in order to guide the weights, as has been necessary in the constructional forms having become known up to now. Another advantage of this new construction is that the weights can be given a size rendering it actually possible to balance the action of the centrifugal force upon the blades which is highly favorable for the efficiency of the machine. Owing to the avoidance of recesses in the blades, as mentioned, the manufacture of them is greatly simplified and the manufacturing costs are greatly reduced, and as the dimensions of the machine can be reduced without any reduction of the output, a corresponding amount of the high-grade material requisite for the machine is saved which entails further savings as regards the manufactured costs.

In the constructional forms shown by way of example there are two blades, but it is a matter of course that, for instance, also four blades may be provided in which case the rotor will consist of four quadrants instead of two halves. The quadrants are connected with one another also by disks like *f*, and there are then two diametrically extending slots arranged at right angles with respect to one another. In the example shown each blade consists of one piece extending from the one frontal side to the other frontal

side of the rotor and having uniform transverse section throughout its entire length. This is true also of the balance weights, but as regards these latter, I wish it to be understood that instead of a continuous weight, such as b or b_1 , a plurality of smaller weights arranged in a series may be used, as is indicated in Fig. 3 in which b_2 indicates the row of such smaller weights.

If the machine is provided with four blades, of course in connection with a corresponding number of balance weights, the advantages obtainable by the machine will be still greater in every respect.

I claim:

1. A rotary machine, comprising, in combination, a stationary casing, a rotor arranged eccentrically in said casing and provided with a slot extending diametrically through it, blades arranged in said slot in the end portions thereof and contacting at their outermost faces with the inner circumferential surface of said casing, balance weights likewise arranged in said slot near to the innermost faces of said blades and pro-

vided with radial bores, rods affixed to the said blades at the innermost faces of the same and extending through the bores of the adjacent balance weights and being firmly connected at the other end with the there located balance weight.

2. A rotary machine as specified in claim 1, in which the connecting rods extending from any of the blades to the oppositely located balance weight constitute guide members for the balance weight, through the bores of which they extend.

3. A rotary machine as specified in claim 1, in which the connecting rods extending from one of the blades to the oppositely located balance weight and from the other blade to the oppositely located balance weight alternate with one another.

4. A rotary machine as specified in claim 1, in which each balance weight consists of a plurality of parts of equal transverse section arranged side by side parallel to the longitudinal axis of the machine.

OTTO SORGE.
